SECOND STAGE PRESSURE REGULATOR FOR UNDERWATER BREATHING APPARATUS

Earl M. Shugarman, Costa Mesa, Calif., assignor to
W. J. Voit Rubber Corp., a corporation of California

Filed Aug. 5, 1964, Ser. No. 81,169

Term of patent 3½ years

(Cl. D83—1)

FIG. 1.

FIG. 2.

FIG. 3.

FIGURE 1 is a perspective view of a second stage pressure regulator, showing my new design;

FIGURE 2 is a perspective view as seen from the opposite side of FIGURE 1; and

FIGURE 3 is a plan view taken from the bottom of FIGURE 1.

I claim:

The ornamental design for a second stage pressure regulator for underwater breathing apparatus, substantially as shown.
